UNITED STATES PATENT OFFICE

130,367

DESIGN FOR A TEXTILE FABRIC

Arthur B. Capper and Rudd Fuller,
Charlotte, N. C.

Application August 25, 1941, Serial No. 103,009

Term of patent 3½ years

To all whom it may concern:

Be it known that we, Arthur B. Capper and Rudd Fuller, citizens of the United States, residing in the city of Charlotte, county of Mecklenburg, and State of North Carolina, have invented a new, original, and ornamental Design for a Textile Fabric, of which the following is a specification, reference being had to the accompanying drawing, forming part thereof.

The figure is a plan view of a piece of textile fabric, showing our new design.

We claim:

The ornamental design for a textile fabric, substantially as shown.

ARTHUR B. CAPPER.
RUDD FULLER.
